(57) **CLAIM**

The ornamental design for a weatherproof cover for ski pole, as shown and described.

DESCRIPTION

1. Weatherproof cover for ski pole

1.1 : Perspective

1.2 : Front

1.3 : Back

1.4 : Left

1.5 : Right

1.6 : Top

1.7 : Bottom

1.8 : Reference figure

1.9 : Reference figure

The material is synthetic material; this design relates to a weatherproof cover that can be joined to a ski pole or climbing pole (stick) to cover the hand; reference figure 1.8 is a drawing showing the present design related to a ski pole, reference figure 1.9 is a view showing a folded shape of a weatherproof cover of the present design related to a ski pole.
